BURIAL VAULT

George W. Tarvin, Parsons, Kans.

Application January 31, 1933, Serial No. 654,531

1 Claim. (Cl. 27—17)

The invention relates to a burial vault.

The primary object of the invention is the provision of a vault of this character, wherein the body and top or cover thereof are joined in a novel manner so as to render the vault waterproof and when the same is within the ground it will withstand moisture and maximum life thereto will be assured.

Another object of the invention is the provision of a vault of this character, wherein the body and top or cover are made from sheet metal, the body being formed with a marginal rim which can be lap seamed over the edge of the top or cover and hermetically sealed so as to exclude moisture and water and at the same time preserving a body held therein, the lap seam being of novel construction so as to assure the complete sealing of the top or cover with the body.

20 A further object of the invention is the provision of a vault of this character which is extremely simple in construction, thoroughly reliable and efficient in its purposes, strong, durable, and inexpensive to manufacture.

25 With these and other objects in view, the invention consists in the features of construction, combination and arrangement of parts as will be hereinafter more fully described in detail, illustrated in the accompanying drawings, 30 which disclose the preferred embodiment of the invention, and pointed out in the claim hereunto appended.

In the accompanying drawings:

Figure 1 is a top plan view of a vault constructed in accordance with the invention showing the cover or top thereof partly broken away.

Figure 2 is a side elevation, the body and top or cover being partly broken away.

40 Figure 3 is an enlarged fragmentary vertical transverse sectional view showing in detail the sealing of the cover or top with the body.

Figure 4 is a view similar to Figure 3 showing the cover or top separated from the body of the 45 vault.

Figure 5 is a perspective view of the cover or top, the same being partly broken away.

Figure 6 is a fragmentary perspective view of one side of the body of the vault.

50 Figure 7 is an end elevation of the vault when closed.

Similar reference characters indicate corresponding parts throughout the several views in the drawings.

55 Referring to the drawings in detail, the vault

comprises a box-like body 10, preferably made from sheet metal, as for example, galvanized sheet metal, although it may be made from any other suitable material and constitutes a unit in itself with sealed corner edges. The body 10 is closed at its bottom and open at its top and at the top opening exteriorly thereof is riveted or otherwise secured an angle strip or bar 11, preferably of iron and the same being extended throughout the sides and ends of the body. This angle strip is of substantially inverted L form. The sides and ends of the body 10 are extended laterally to provide an overlapped flange 12 for the strip 11, the flange 12 being riveted or otherwise made secure to said strip 11 and an upstanding bendable overlapped seaming flange 13 for a purpose presently described.

The top or cover for the body 10 includes an outer upwardly bulged section 14 and an inner lining section 15 respectively, the latter being of dish formation. These sections 14 and 15 are marginally joined at the flanged edges 16 and 17 respectively, which are riveted together at 18, while interiorly of the top or cover between said sections 14 and 15 are longitudinal and transverse reinforcements 19 and 20 respectively, these being interfitted and materially strengthen the top or cover to withstand any strain imposed thereon and prevent collapse due to the pressure of the soil thereagainst when the vault may be buried within the ground.

Normally the flanges 13 upstanding from the flanges 12 are vertically disposed and after a body is placed within the vault the cover or top is telescoped within the opening upper portion of the body 10 of the vault so that the flanges 16 and 17 will be superimposed upon the flanges 12 and in this fashion the body 10 is closed. Thereafter the flanges 13 are bent inwardly and downwardly into overlapping relation to the flanges 16 and 17 as is clearly shown in Figure 3 of the drawings so that an overlapped seam or joint is had between the top or cover and the body 10 of the vault.

Finally the flange 13 at its free edge is soldered or otherwise joined as at 21 with the flange 16, this soldering being carried out throughout the sides and ends of the body 10 and thus it will be seen that the vault will be hermetically sealed so as to exclude moisture and water therefrom and particularly when buried within the soil.

The angle strip 11 exteriorly of the body 10 materially strengthens the latter.

The body 10 at each side thereof carries suit-

able hand holds 22 for convenience in the handling of the vault.

Arranged interiorly of the body 10 and disposed vertically at the sides thereof and transversely at the bottom of the same are substantially U-shaped braces 23, it being preferable to employ at least three of the same and such braces are either soldered or riveted in place, the transverse portions of such braces being 10 adapted to function as a rest for a casket when placed within the body 10 and also to space such casket from the body to enable ventilation about the casket. The braces 23 also serve to strengthen the walls of the vault or the body 15 thereof. The vertical portions of the braces terminate next to the angle pieces 11 so as not to interfere with the telescoping of the top or cover in the body 10, the ends of the vertical portions of said braces 23 being rounded as 20 shown.

It is to be understood that in the use of the burial vault the same is to be set in concrete after the same has been lowered into the ground.

Furthermore, the vault in its entirety is to be 25

covered with an aluminum paint for protection and artistic design both inside and outside of such vault although it is to be understood that the color of the paint may be varied at the option of the purchaser of the vault.

80

What is claimed is:

A burial vault comprising a body having sides, ends bottom and open top, an angle strip secured exteriorly of said body, a lateral flange on the sides and ends to be disposed entirely about the open top and overlapping said angle strip, a cover telescoped within the open top of said body and including upper and lower members, a lateral flange entirely about the cover and formed with the members to rest upon the flange on the body, rivets joining the upper and lower members of the cover flange, other rivets joining the body, its flange and angle strip, a bendable seaming flange joined with the flange of the body and folded inwardly onto the flange of the cover, and solder uniting the seaming flange with the flange of the cover.
